(57) **CLAIM**

I claim the ornamental design for a clip, as shown and described.

DESCRIPTION

FIG. 1 is a front perspective view of the clip; FIG. 2 is a top view of the clip of FIG. 1; FIG. 3 is a left-side view of the clip of FIG. 1; FIG. 4 is a right-side view of the clip of FIG. 1; FIG. 5 is a bottom view of the clip of FIG. 1; FIG. 6 is a front view of the clip of FIG. 1; FIG. 7 is a rear perspective view of the clip of FIG. 1; and, FIG. 8 is a top perspective view of the clip, shown in use with environment. The broken lines depict environment that form no part of the claimed design.
